PAVING DOWEL SUPPORTING CONSTRUCTION

Thomas C. Salisbury, San Dimas, Calif., assignor, by
mesne assignments, to P. B. A. Company, Alhambra,
Calif., a corporation of California

Application August 31, 1953, Serial No. 377,373

1 Claim. (Cl. 25—118)

This invention relates to a paving dowel supporting construction and, more particularly, to a paving dowel supporting construction which includes a paving header for defining the lateral edge of a roadway or other concrete construction and a keyway channel, said channel being provided with means for supporting a plurality of paving dowels in predetermined relationship with one another and a prepared surface upon which concrete is to be poured.

It is conventional practice, at the present time, in laying concrete roadways, airstrips, and other analogous structures to utilize reinforcing dowels which are constituted by a stud member which is threaded at one end, said stud member being mounted in a conventional keyway channel on a paving header and being threaded at its outer end to receive a mating nut. After the concrete has been poured and the paving iron and keyway channel removed, an additional paving dowel having a threaded end is screwed into the mating nut. Recent advances in the cost of raw steel stock and the cost of fabricating the same have led to greatly increased costs in the fabricating of the aforementioned conventional dowel structures and efforts have been made to utilize paving dowels constituted by elongated bars, one end of each of which is inserted in the paving concrete during the pouring thereof, while the other end thereof is bent at a right angle, said bent right-angle portion being mounted within a conventional keyway channel to support the same.

However, serious difficulties have arisen because of the utilization of such conventional constructions in supporting the right-angularly bent paving dowels, among them being the fact that when such right-angularly bent paving dowels have been installed with the right-angularly bent legs thereof within a conventional channel, it is necessary to straighten them to remove the channel and it is then frequently necessary to once again bend them to permit the passage of road-building equipment without the danger of breaking off or destroying the extending ends of the paving dowels. Repeated bending of the paving dowels causes crystallization at the bend points of the dowels and frequently results in the breakage thereof.

Furthermore, it is necessary to permit the concrete to cure for a predetermined time before the channel can be removed by straightening the right-angularly bent legs of the dowels to permit such removal.

It is, therefore, an object of my invention to provide a paving dowel support construction which includes a conventional paving header having mounted thereupon a keyway channel which includes an intermediate form face or wall, said form wall being provided with a recess in the face thereof which is designed to receive the right-angularly bent legs of a plurality of paving dowels. The manifest advantages of the supporting construction of my invention include the fact that it is not necessary to subject the paving dowels to repeated bending since, when the paving dowels have their right-angularly bent legs

2

disposed in predetermined relationship within the recess in the face of the form wall of the channel and the concrete has been poured to embed the extending legs thereof in said concrete, the paving header and its associated keyway channel can be readily removed from operative relation with the concrete after a relatively short period of time due to the fact that the right-angularly bent legs of the paving dowels do not have to be bent to release the keyway channel from operative engagement therewith.

10 Another object of my invention is the provision of a paving dowel supporting structure in which the recess in the face of the keyway channel is constituted by an elongated groove into which the right-angularly bent legs of the paving dowel are inserted to maintain said paving dowels in spaced relation with one another and with a previously prepared surface upon which concrete is to be poured.

20 An additional object of my invention is the provision of a paving dowel supporting structure which includes fastening means for maintaining the right-angularly bent legs of the paving dowels in operative relationship with the aforementioned recess in the face of the keyway channel to prevent dislocation of said right-angularly bent legs from operative engagement with said recess.

25 An additional object of my invention is the provision, in a paving dowel supporting structure of the aforementioned character of fastening means constituted by spring clips whose opposite ends are insertable in openings provided in the face of the keyway channel, said spring clips being designed to restrain the right-angularly bent legs of the paving dowels against inadvertent dislocation from the recess in the face of the keyway channel.

35 The utilization of spring clips is advantageous in that it permits the keyway channel to be readily removed from operative engagement with the right-angularly bent legs of the paving dowels by merely prying the keyway channel outwardly out of engagement with the keyway formed in the edge of the concrete structure, thus readily releasing the keyway from operative engagement with the right-angularly bent legs and completely eliminating the necessity for bending and re-bending said legs.

40 An additional object of my invention is the provision of a dowel supporting structure of the aforementioned character which includes an elongated recess for the reception of the right-angularly bent legs of the paving dowels, said elongated recess being constituted by a continuous groove whose longitudinal axis is parallel to the longitudinal axis of said channel, said groove having a configuration which permits it to conform substantially to the external configuration of the right-angularly bent legs of said paving dowels and having a depth which permits the entire cross-sectional area of the paving dowels to be received in the recess.

45 Other objects and advantages of my invention will be apparent from the following specification and the accompanying drawing which is for the purpose of illustration only and in which:

50 Fig. 1 is an isometric view showing a dowel support construction of my invention in operative relationship with a paving dowel and with the adjacent edge of a concrete structure defined by said paving dowel supporting construction;

55 Fig. 2 is a top plan view taken in the direction of the broken line 2—2 of Fig. 1;

60 Fig. 3 is a vertical, sectional view taken on the broken line 3—3 of Fig. 2; and

65 Fig. 4 is a vertical, sectional view taken from the broken line 4—4 of Fig. 2.

70 Referring to the drawing, and particularly to Figs. 1 and 2 thereof, I show a paving dowel support construction 10 manufactured in accordance with the teachings

of my invention and including a conventional paving header or iron 11, said paving header including a base portion 13 which is conventionally pegged or otherwise affixed to a surface 14 upon which a concrete structure such as a roadway is to be laid.

Formed integrally with the base 13 of the paving header 11 is a vertical form wall 15, said form wall being adapted to define the lateral edge 17 of a concrete roadway 18, or other concrete structure. Formed integrally with the upper edge of the vertical form wall 15 of the paving header 11 is a tread or track 19 upon which the wheels of road-laying equipment can ride during the process of laying the concrete roadbed 18. It will be noted that the paving header 11 is constituted from a single piece of relatively heavy gage sheet steel stock and that the base 13, the vertical form wall 15, and the tread or track 19 are integrally formed with one another.

It should also be noted that Fig. 1 of the drawing shows two headers 11 with their ends disposed in abutting relationship with each other and that, therefore, two dowel supporting structures 10 are also shown.

The paving header 11 has mounted upon the vertical form wall 15 thereof a keyway channel 22, said keyway channel including an intermediate form wall 23 which is disposed in spaced relation with the face of the vertical form wall of the paving header 11 by means of angularly oriented, instruck spacer walls 26 and 27 formed integrally therewith. The keyway channel 22 is utilized to form the longitudinal keyway 25 in the lateral edge of the concrete structure or roadway 18 so that an interlocking joint will be provided with an adjacent roadway section.

In order to reinforce the roadway 18, a plurality of paving dowels is utilized which are embedded in the concrete during the pouring thereof. The paving dowels 30 are constituted by right-angularly bent steel bars 31 of substantially cylindrical cross-sectional configuration and are right-angularly bent to provide right-angularly bent positioning legs 33 which provide support for normally extending legs 35, said normally extending legs 35 terminating in ground engaging legs 37 which support them in spaced relation with the surface 14 upon which concrete is to be poured.

A longitudinally extending, elongated dowel receiving and supporting recess 40 is provided in the intermediate form wall 23 of each of the keyway channels 22, said elongated recess being designed to receive the right-angularly bent legs 33 of the dowels 30 to support said dowels in spaced relation with one another and to maintain them in predetermined orientation with the surface 14 during the concrete laying process. The elongated recess 40 in each of the keyway channels 22 is constituted by an elongated groove 41, said groove 41, as best shown in Figs. 3 and 4 of the drawing, being of substantially arcuate cross-sectional configuration to permit it to conform to the peripheral configuration of the right-angularly bent legs 33 of the paving dowel located therein.

It should be noted at this juncture that, in addition to the mating configuration of the elongated groove 41 with the peripheral configuration of the right-angularly bent legs 33 of the paving dowel 30, the depth of the groove 41 is sufficient to permit the entire cross-sectional dimension of the right-angularly bent legs 33 of the associated paving dowels 30 to be received therein so that no portion thereof protrudes beyond the face of the intermediate form wall 23 of the keyway channel 22. In addition, the width of the groove 41, as indicated by the line A in Fig. 4 of the drawing, is slightly greater than the cross-sectional width of the right-angularly bent legs 33 of the associated paving dowels 30 so that the right-angularly bent legs 33 can be readily received in the groove 41.

In order to maintain the paving dowels 30 in operative relation with the grooves 41 in the intermediate

form walls 23 of the keyway channels 22, fastening means 46 are provided, said fastening means being constituted in one instance, as best shown in Fig. 3 of the drawing, by tie wires 47, the free ends of which are inserted through openings 49 in the intermediate form wall 23 of the keyway channel 22 and tied in a knot 51 to restrain the right-angularly bent legs 33 of the paving dowels 30 from dislocation from the elongated groove 41 in said keyway channel.

An alternative type of fastening means is provided, as best shown in Fig. 4 of the drawing, by a spring clip 55 which may be formed from either spring sheet or spring wire stock and which has its opposite ends insertable through the aforesaid openings 49 in the intermediate form wall 23 of the keyway channel 22 to maintain the right-angularly bent legs 33 of the paving dowels 30 in operative engagement with the groove 41.

In order to maintain the keyway channel 22 in operative relationship with the header 11, mounting means 60 is provided, said mounting means being constituted by U-shaped mounting brackets 61 whose ends are welded to the inner wall of the groove 41, as best shown in Figs. 2 and 4 of the drawing.

The U-shaped mounting brackets 61 are receivable in and extend through longitudinally spaced openings 63 provided in the vertical form wall 15 of the paving header 11, as best shown in Fig. 4 of the drawing, and are engaged by spring clips 65, said spring clips preventing the inadvertent separation of the keyway channel 22 from the paving header 11.

The manner in which the paving dowel supporting construction of my invention may be utilized is as follows: The right-angularly bent legs 33 of the paving dowels 30 are first disposed in operative engagement within the recesses 40 in the intermediate form walls 23 of the keyway channels 22 and are restrained from dislocation therefrom by the utilization of fastening means 46, such as the tie wires 47 or the spring clips 55 which are inserted through the openings 49 in the intermediate form wall 23 and, in the case of the tie wires 47, knotted, as at 51.

The U-shaped mounting brackets 61 are then inserted through the longitudinally spaced openings 63 in the vertical form wall 15 of the paving header 11 and the spring clips 65 are then inserted through the U-shaped mounting brackets 61 to maintain the elongated keyway channels 22 in predetermined relationship upon the vertical form wall 15 of the paving header 11. The paving headers 11 are then pegged to a prepared surface 14 and the concrete roadway 18 is poured.

After a relatively short curing period, the paving headers 11 are disengaged from operative relationship with the keyway channels 22 by removing the spring clips 65 from the U-shaped mounting brackets 61 and laterally displacing the paving headers 11 to cause the mounting brackets 61 to pass through the openings 63 in the vertical form walls 15 of the paving headers 11. If tie wires 47 are utilized as fastening means 46, they are then clipped and the elongated keyway channels 22 pried out of the keyways 25 formed thereby in the lateral edge 17 of the concrete roadway 18. If spring clips 55 are utilized, it is merely necessary to pry the elongated keyway channels 22 out of engagement with the keyway 25, thus releasing the keyway channels 22 from operative engagement with the right-angularly bent legs 33 of the paving dowels 30 without the necessity for bending the paving dowels prior to such release.

This is a manifest advantage over the prior art since a relatively short curing time is necessary to permit the paving header 11 and the keyway channels 22 to be removed from operative engagement with the lateral edge 17 of the concrete roadway 18 if there is no necessity for bending the right-angularly bent legs 33 of the paving dowels 30.

Furthermore, there is a great saving in time and labor since it is not necessary to bend the right-angularly bent

legs 33 of the paving dowels 30 outwardly to free the keyway channel from operative engagement with the lateral edge 17 of the roadway 18, nor is it necessary subsequently to rebend the right-angularly bent legs 33 of the paving dowels 30 into their originally bent position to prevent the destruction thereof by roadworking equipment. In addition, the crystallization of the dowels and the breakage thereof encountered because of continual and repeated bending of the right-angularly bent legs 33 thereof is eliminated since it is only necessary to bend the right-angularly bent legs 33 thereof outwardly when the adjoining concrete strip is to be poured.

It should be noted, as best shown in Fig. 1 of the drawing, that a right-angularly bent leg 33 of a paving dowel 30 can be inserted in the contiguous recesses 40 of adjacent elongated keyway channels 22, thus serving as a mating member to accurately align the keyway channels 22 and the associated paving headers 11.

I thus provide by my invention a paving dowel supporting construction which is characterized by extreme ease of assembling the dowels in supporting relationship therewith and which is also characterized by the ease of disassembly thereof from operative relationship with said dowels. Furthermore, the breakage of dowels incident to the use of conventional dowel supporting constructions is eliminated and, due to the fact that the paving dowel supporting construction of my invention can be dismantled from operative relationship with a poured roadway or other concrete construction after a relatively short period of time, there is no necessity to provide a large number of paving dowel support constructions since the paving dowel support constructions of my invention can be utilized repeatedly during the same job because of the relatively short curing time necessary before the dowel support construction of my invention is removed from operative relation with a concrete structure which has been poured by the use thereof.

The keyway channel 22 can also be used to support reinforcing dowels in a vertical plane, as at the edge of a tilt-up panel. To accomplish this desired end, the keyway channel 22 is supported at the ends of, for example, a tilt-up form with the dowels having their free ends extending into the concrete as it is poured. Subsequently, when the panel is erected, the dowels can be bent outwardly to free the keyway channel from the panel.

I claim as my invention:

- 10 5 In a dowel supporting construction for supporting a plurality of paving dowels in predetermined, spaced relation and for defining the edge of a concrete structure in which portions of said dowels are embedded, the combination of: a paving header, said header including a base and a vertical form wall on said base, said form wall having a plurality of longitudinally spaced fastener receiving openings therein; an elongated keyway channel removably secured to said form wall intermediate the upper and lower edges thereof, said keyway channel having a vertical, 15 intermediate wall disposed in spaced relation with said form wall, said intermediate wall having a continuous groove provided in the face thereof defined by a rearwardly extending, continuous protrusion in said intermediate wall for the reception of a plurality of dowels; 20 said groove being of arcuate cross section at the bottom thereof to prevent seepage of concrete between the dowels and the bottom of the groove and the diameter of said groove being substantially the same as the diameter of said dowels; and fastener means extending through said 25 openings in said form wall for demountably maintaining said channel thereupon.
